CLAIM

The ornamental design for a octagon-shaped housing and control panel for an air-moving device, as shown and described.

DESCRIPTION

FIG. 1 is a perspective view of the octagon-shaped housing and control panel for an air-moving device showing my new design;

FIG. 2 is a front view of my new design;

FIG. 3 is a left side view of my new design;

FIG. 4 is a right side view of my new design; and,

FIG. 5 is a top view of my new design.

The broken lines shown on the face of the control panel depict portions of the octagon-shaped housing and control panel for an air-moving device that form no part of the claimed design, while all other broken lines depict environmental structure that form no part of the claim.

The unshaded surface of the control panel shown between the broken lines and solid lines forms no part of the claimed design.

1 Claim, 5 Drawing Sheets
